UNITED STATES PATENT OFFICE.

EBER H. VAN VALKENBERG, OF MONROE, WASHINGTON, ASSIGNOR OF ONE-HALF TO OSCAR SILVERSTEIN, OF SPOKANE, WASHINGTON.

BALLASTING MEANS.

Application filed April 27, 1925. Serial No. 26,083.

To all whom it may concern:

Be it known that I, EBER H. VAN VALKENBERG, a citizen of the United States, residing at Monroe, in Snohomish County and 5 State of Washington, have invented certain new and useful Improvements in Ballasting Means, of which the following is a specification.

The present invention relates to improvements in ballasting means especially adapted for use in maintaining the equilibrium or an even keel of dirigible aircraft or the lighter-than-air type of air ships.

The invention contemplates the utilization 15 of water, carried in a tank suspended from the craft, as an agency for this purpose, and the tank is preferably located beneath the gondola or car of the ship. Means are provided whereby the supply of water may be 20 replenished while the aircraft is underway thus avoiding the necessity for stopping the ship for this purpose, and also for eliminating unnecessary landings during the course of a cruise or trip undertaken by the ship.

25 Means are provided for dispensing with a required or predetermined quantity of water from the ballast tank if necessary for lightening the ship during its progress, as for instance in order to more quickly ascend.

30 For the purpose of accomplishing these ends and otherwise improving the construction and operation of the ship, the invention consists in certain novel combinations and arrangements of parts as will hereinafter be 35 more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a longitudinal sectional view 45 along the keel line of an air craft showing a portion of the lower part of the gondola or car, and the water-ballast tank with intake and outlet control mechanism for the water-ballast.

Figure 2 is a top plan view showing the 50 intake scoop for the tank, at line 2-2 of Figure 1.

Figure 3 is a view showing a portion of the intake scoop and its control device with 55 part of the tank and gondola in vertical section.

Figure 4 is a transverse vertical sectional view of a gondola showing the water beneath the same and illustrating the manner of suspending the gondola from the airship part of which is also shown in section. 60

The portions of the aircraft illustrated in the drawings show a hull with a double wall as 1 and 2, and beneath the hull extending parallel with the keel line are spaced, longitudinally extending suspending-tracks 3 and 4 upon which the gondola or car 5 is carried and adapted to be moved fore and aft of the ship for maintaining its equilibrium. On the upper deck or roof of the car are carried two series of two-wheel trucks 6 65 provided in suitable number and supported by hangers 7 for the purpose of suspending the car from the ship. In Figure 4 a motive fluid mechanism is indicated at 8 which includes co-acting means on the ship and car located on the keel line of the ship, for relatively moving the ship and car. 70

Beneath the gondola or car is carried the ballast-tank 9 which is of suitable capacity commensurate with the size of the ship for carrying the water-ballast, and constructed with a hull portion of the ship as 10 forming the top of the tank. The tank extends fore and aft of the gondola, and as shown in Figure 4 is of the same width as the gondola 75 or car with its sides equidistant from the keel line of the ship. 80

Within the tank are provided suitable braces of which the transverse members 11 form baffle walls or plates to prevent excessive bodily movement of the bulk of water in the tank. At their ends these transverse braces have diagonally extending parts 12 which further assist in retarding the movement of the bulk of the water and prevent 85 impingement of the bulk against the ends of the tank. 90

Longitudinally extending braces 13 are also provided along the bottom and top of the tank to hold rigid the transverse braces 100 and reinforce the tank structure against strains due to movement of the water-ballast.

At the forward end of the tank is provided a transversely extending intake opening 14, which as shown in Figure 1 is located at the upper part of the tank. This opening is normally closed by a hinged scoop 15, which is adapted to swing from open full line position to closed dotted line position in Figure 1 to close the intake opening 110

against entry of air currents while the ship is under way, and to form a protecting shield for the tank against any abutment that may be encountered while landing.

5 At its opposite ends the scoop is provided with perforated ears 16 through which horizontally aligned pivot bolts 17 pass, said bolts being fixed in the side walls of the tank as indicated in Figure 2, and the inclined face 18 plate 15' of the scoop is slotted as at 18 to accommodate the scoop as it swings up to dotted position in Figure 1, said slots passing over the edges 19 of the tank walls.

This slotted formation of the scoop in combination with the edges 19 assists in guiding the scoop in its movements and retains the scoop against lateral strains or movements, when the scoop is in normal dotted position of Figure 1.

20 The scoop is lowered by means manipulated or controlled from the interior of the car as indicated in Figure 1, and a screw bar 20 is used for lowering or raising the scoop on the hinges 17. This screw bar 25 passes through the bottom of the gondola or car and through a slot 20' in the inclined plate 15' of the scoop, and at its lower end the screw bar is pivoted on a transversely extending bar 21 supported in the scoop, the 30 connection between the bar 20 and 21 being made by an eye or hub 22 on the screw bar.

Within the gondola a non-traveling nut 23 is provided for the screw bar and supported in brackets 24 in such manner that the nut 35 may oscillate to compensate for the relative movement between the screw bar and the scoop when the latter is being operated. It will be apparent that by turning the screw bar (through the instrumentality of its 40 wheel 20') within the nut the scoop may be lowered to full line position in Figure 1. While in this position the airship may descend to a lake, river or other body of water, skim over the surface with the scoop in 45 position to gather a supply of water that is transferred to the tank, and then ascend, without material interruption to its travel. After the supply has been secured the wheel 20' is turned to close the scoop against the 50 intake opening of the tank.

For dispensing with a quantity of water-ballast from the tank I utilize an outlet port or ports 25 at the rear of tank 9, said port or ports extending transversely of the rear 55 wall and near the bottom of the tank.

The outlet of water through this port is controlled by a vertically arranged slide gate or valve plate 26, which is movable in flanged guide plates 27 attached at the inner side of 60 the rear wall of the tank. A screw bar or

valve stem 28 is connected to the gate valve, by means of a head 29 that permits rotation of the screw bar, and the bar as shown in Figure 1 passes up through an opening in the floor or deck of the gondola. On the 65 threaded end of the screw bar, is a non-traveling nut 30 supported in brackets 31 secured to the floor of the car, and the hand wheel 32 is employed to turn the bar to lift the gate valve to open position or to depress 70 the valve to closed position indicated in Figure 1. It will be apparent that by opening the valve the water may escape through the port 25 to release the ballast and lighten the ship as required. 75

Beneath the gondola or car I have indicated supporting wheels 33 journaled in wheel frames 34 secured to the bottom of the tank, upon which the ship may travel in landing and launching, to protect the 80 tank.

Having thus fully described my invention, what I claim as new and desire to secure by Letters Patent is—

1. In an airship, the combination with a 85 water-ballast tank carried thereby and provided with intake and outlet ports, of a hinged scoop adapted to normally close the intake port, means for adjusting the scoop for opening the port, and means for controlling the outlet port.

2. In an airship the combination with a water-ballast tank carried thereby and provided with an intake port, of an adjustable scoop adapted to normally close the intake 95 port, and means for adjusting said scoop whereby water may be supplied to the tank as described.

3. The combination with a water-ballast tank having an intake port, of a scoop 100 hinged to said tank and normally adapted to close the port, a screw bar connected to the scoop, and a non-traveling nut for said screw bar.

4. In an airship the combination with a 105 water ballast-tank carried thereby and provided with an intake port, of baffle means within said tank for the bulk of water, an adjustable scoop adapted to normally close said port, and means for adjusting said 110 scoop whereby water may be supplied to the tank as described.

5. The combination with a water-ballast tank having an intake port and free edges at its sides, of a slotted scoop hinged to said tank, a screw bar connected to the scoop, and a non-traveling nut for said bar. 115

In testimony whereof I affix my signature.

EBER H. VAN VALKENBERG.
